GOVERNOR

Filed April 16, 1931

UNITED STATES PATENT OFFICE

ARTHUR SINGER, OF CHICAGO, ILLINOIS, ASSIGNOR, BY MESNE ASSIGNMENTS, TO CHICAGO GOVERNOR & MANUFACTURING CO., OF CHICAGO, ILLINOIS, A CORPORATION OF ILLINOIS

GOVERNOR

Application filed April 16, 1931. Serial No. 530,609.

This invention has to do with governors of the type commonly applied to the engines of trucks, busses, taxicabs and other vehicles for the purpose of limiting both the engine and 5 road speeds of the vehicle.

One of the principal objects of the invention is to provide a governor of the type described in which the adjusting parts, as well as the operating parts, are completely enclosed, resulting in a mechanism which is air-tight, water-tight, dust-tight and tamper-proof.

Another important object of the invention is to provide, in such a governor, novel means 15 for increasing the flexibility, sensitiveness and accuracy of the mechanism under the suction to which the same is subjected in use.

Still another important object is to provide, in such a governor, novel means for facilitating ready adjustment of the mechanism.

While the foregoing statements are indicative in a general way of the nature of the invention, other more specific objects and advantages will be apparent to those skilled in the art upon a full understanding of the construction, arrangement and operation of the improved governor.

In order that the invention may be readily 30 understood, two different embodiments of the same are presented herein, but it will of course be appreciated that such forms are intended primarily for the purpose of illustration and that the invention is susceptible of 35 embodiment in other structurally modified forms coming equally within the scope of the appended claims.

In the accompanying drawing:

Fig. 1 is a face view of the improved governor;

Fig. 2 is a face view of the governor with the cover plate removed, showing the suction-controlled valve of the governor in its fully opened position;

Fig. 3 is a view similar to Fig. 2, showing the valve in its closed position;

Fig. 4 is a horizontal section through the governor, taken on the line 4-4 of Fig. 2; and

Fig. 5 is a face view of a modified form of

the governor, with the cover plate removed.

The form of governor shown in Figs. 1 to 4 inclusive will first be described. The governor—which is adapted to be installed in the vaporized fuel line 10 of the engine between the carburetor 11 and the intake manifold 12—includes a body 13 which is adapted to be clamped by bolts 14 between coupling flanges 15 and 16 formed respectively on the opposing portions of the carburetor and intake manifold. The body 13 contains a vaporized fuel passage 17 in register with the line 10. The passage 17 is preferably of rectangular cross section, except at its lower end 18, where it is preferably of enlarged upwardly converging circular cross section.

A valve 19, which is of the same shape as the cross sectional area of the passage 17, is positioned in the upper portion of the passage and is attached by a screw 20 to a shaft 21 which is rotatably journaled in the body in a position crosswise of the passage. One end of the shaft 21 projects from the body into the interior of a flat casing 22, which casing is attached by screws 23 to the body, 75 although it may as well be formed as an integral part of the same.

The casing 22 is of generally rectangular shape and is provided at its front with a removable cover plate 24. The edges of the 80 cover plate are sealed against the rim 25 of the casing by an interposed gasket 26 which is secured to the inside face of the cover plate, and the cover plate is held in place by a screw 27 which extends through a hole in 85 the center of the cover plate and engages within a screw-threaded bore in a stud 28 which is attached to the back of the casing.

When the screw 27 is drawn up tight, the edges of the cover plate 24 seal tightly 90 against the rim of the casing 22, thereby rendering the casing water-tight, air-tight and dust-tight. After the screw 25 has been drawn up tight, it may be maintained in that position by the insertion therethrough 95 of a sealing wire 29, which wire may also be inserted through one end of one of the bolts 14, thereby preventing any unauthorized person from tampering with the adjustment of the mechanism located within the casing. 100

The end of the shaft 21 which projects into the casing 22 carries a downwardly extending arm 30, which arm is provided near its lower end with an adjusting screw 31 which engages with one side of the stud 28 to determine the open position of the valve 19 in the passage 17.

The valve 19 is normally maintained in its open position by a special spring arrangement consisting of three springs 32, 33 and 34, all of which are connected together at 35 in a generally T-shaped formation. The spring 32 is anchored at its upper end to the casing by a pin 36 over which it is hooked; 10 the spring 33 is anchored at its lower end to the casing by a pin 37 over which it is hooked; and the spring 34 is telescoped at one end over, and fixedly secured to, a sleeve 38 which terminates beyond the end of the 15 spring in an enlarged nut formation 39. The nut 39 is screwed onto a threaded link 40 which terminates in an eye 41, and the eye 41 is detachably hooked over a pin 42 on the 20 lower end of the arm 30.

25 The suction in the vaporized fuel passage 17 caused by the operation of the engine acts upon the valve 19, tending to close the latter against the resistance of the springs 32, 33 and 34. As the speed of the engine approaches the predetermined maximum speed 30 for which the governor mechanism has been set, the valve 19 will move against the yielding resistance of the springs toward its closed 35 position. It is desirable that the initial movement of the valve toward its closed position meet with but little resistance, since in the fully open position of the valve even a strong suction has but very little effect on the same. But as the valve continues to close, 40 and is acted upon more strongly by the consequently increased suction past the edge thereof, it is desirable that the springs afford a progressively increasing amount of 45 resistance to the closing movement.

45 The plural spring arrangement shown herein, illustrated and described, is ideally suited for this purpose. When the valve 19 starts to close, only the spring 32—which is 50 comparatively weak—will resist the closing movement. As the closing progresses, the spring 33 will come into play, and, after the V-shaped spring formation shown in Fig. 3 has been produced, the relatively strong 55 spring 34 will proceed to yield, giving a very flexible, highly sensitive and accurately compensating action.

60 Adjustment of the governor to increase or decrease the maximum speed setting may be accomplished very easily. It is merely necessary to remove the outer cover plate 24, unhook the eye 41 of the adjustable turn-buckle arrangement from the pin 42, and rotate the link 40 one or two turns into or out of the nut 39, or whatever amount is necessary 65 or prescribed to give the desired speed

setting. After the adjustment has been made, the eye 41 is hooked back onto the pin 42 again and the cover plate 24 is replaced.

Since all of the working and adjusting parts of the mechanism are totally enclosed 70 within the casing 22 behind the sealed cover plate 24, the mechanism is rendered watertight, dust-tight, air-tight and tamper-proof. By having the mechanism air-tight, there is no danger of air being sucked into the casing and passing through the body along the shaft 21 into the passage 17, which seepage, if permitted, would interfere with the accuracy of the operation of the mechanism.

In Fig. 5 is shown a modification of the 80 invention in which only two springs 43 and 44—corresponding to the springs 32 and 33—are used, and those springs are connected directly to the outer end of a link 45. The link 45 is threaded adjacent its other end and carries an elongated nut 46 which is provided with an annular groove 47. The arm 48 which is attached to the valve shaft 49 is provided at its lower end with a laterally opening notch 50 which interfits laterally with the groove 47 in the nut. In this form of the invention, as in the other form, one of the springs, and preferably the spring 43, yields before the other. Adjustment of the spring resistances may be easily effected by moving the nut 46 laterally out of the notch 50 and turning the nut in one direction or the other on the link 45.

I claim:

1. In a governor for use with internal combustion engines, a body having a vaporized-fuel passage, a suction-operated valve in the passage, and a plurality of consecutively yieldable springs pivotally connected with each other for holding the valve open. 100

2. In a governor for use with internal combustion engines, a body having a vaporized-fuel passage, a suction-operated valve in the passage, and a plurality of consecutively yieldable springs connected together at one point in—a generally T-shaped formation and connected with the valve through one of the springs for holding the valve open. 110

3. In a governor for use with internal combustion engines, a body having a vaporized fuel passage, a suction-operated valve in the passage, a rotatable shaft on which the valve is mounted, an arm on the shaft, a plurality of consecutively yieldable angularly movable springs pivotally connected with each other, and a link pivotally connected to the springs at their pivotal connection and also pivotally connected with the arm.

4. In a governor for use with the internal combustion engines, a body having a vaporized-fuel passage, a suction-operated valve in the passage, a rotatable shaft on which the valve is mounted, an arm on the shaft, adjustable spring means for holding the valve open, and a laterally separable pivoted con-

nection between the arm and said means for permitting adjustment of the latter.

5. In a governor for use with internal combustion engines, a body having a vaporized-fuel passage, a suction-operated valve in the passage, a rotatable shaft on which the valve is mounted, an arm on the shaft, spring means for holding the valve open, and a turn-buckle arrangement connected with the said 10 means and having a laterally separable connection with the arm for permitting adjustment of said means.

6. In a governor for use with internal combustion engines, a body having a vaporized-fuel passage, a suction-operated valve in the passage, and a plurality of angularly movable coil springs pivotally connected with each other and with the valve for holding the latter open.

20 In testimony whereof I have hereunto subscribed my name.

ARTHUR SINGER.
